SELECTIVE AUDIO RELAY

Paul E. Fischler, Buffalo, N. Y., assignor of one-half to John Nathanson, Buffalo, N. Y.

Application April 1, 1949, Serial No. 84,909

3 Claims. (Cl. 200—91)

1

This invention relates to a selective audio relay which may be tuned to operate at any frequency within the audio spectrum and more specifically to an improved device of this nature which has advantages over the device disclosed in the co-pending application, Serial Number 24,780, filed May 3, 1948, and entitled Tuned Audio Relay.

An object of the invention is to provide a relay of the class described in which leakage paths in the magnetic circuit are reduced to a minimum and the magnetic flux is concentrated at one point, thereby improving the efficiency of the relay.

Another object is the provision of a selective audio relay having improved armature suspension.

A further object is to provide in a relay of the class described a method of assembling the two inductors of the relay in such a manner that their lumped inductance may be accurately adjusted to any operating frequency, thereby affording a means of compensating for production variations in the inductors and capacitors and also allowing the use of one set of inductors for tuning over a narrow band of frequencies.

dust cover 13 cut away to show the face of the relay;

Figure 3 is a view of the relay with the dust cover cut away to show the reverse side of the relay;

Figure 4 is a top view of the relay with the dust cover removed and with the switch and condenser assemblies omitted to clearly show the assembly of the magnetic circuit to the mounting plate; and

Figure 5 is an enlarged view showing the method of armature suspension and adjustment.

Since this device is designed to operate as part of a series or parallel resonant circuit, it is essential that the values of inductance and capacitance at the operating frequency be selected and adjusted to provide proper current or voltage distribution throughout the circuit. For this reason it is necessary to compute the L-C ratio at a given frequency so that the impedance of the circuit at resonance is essentially the D. C. resistance of the circuit components. (Maximum circuit Q.) These ratios are shown in the following table.

25

Values of L, C, R, Z1 and Q for frequencies from 200 to 1800 C. P. S.

Freq.	200	300	400	500	600	700	800	900	1,000	1,200	1,400	1,500	1,600	1,800
L	1.04	1.18	1.34	1.40	.351	.353	.357	.362	.369	.211	.214	.219	.144	.149
C	.60	.24	.118	.074	.20	.146	.110	.086	.068	.087	.06	.052	.068	.052
R				400					100			75		
Z1									500			300		
Q	3.3	5.6	8.4	11.0	13	15.5	18	21	23	21	25	27.5	29	33.6

Another object of the invention is the provision of a plug-in relay of the type described having ample space for mounting of capacitors either singly or in parallel, thereby allowing the use of readily purchasable stock capacitors.

Other objects and advantages will be apparent from the following specification and the accompanying drawings in which by way of illustration a preferred embodiment of the device is disclosed.

It will be understood, however, that the invention is not limited to this disclosure, as many modifications and changes therein may be made, the invention being as defined by the appended claims.

Referring to the drawings:

Figure 1 is a bottom view of the relay showing the Bakelite base plate and connecting plug thereof;

Figure 2 is a side view of the relay with the

In practice values of R and Z1 are maintained for several frequencies. (This is shown by arrows on chart.)

40

L is given in henries

C is given in microfarads

R is given in ohms

Z1 is given in ohms

Q=Figure of merit

45

Referring to Fig. 1 it will be seen that the relay has a base plate 10 on which is mounted a standard type 4-prong connector plug 36. The base plate is secured to the mounting plate 14 by means of screws 11 and 12 and is provided with a dust cover or cap 13 which is shown in Figs. 2 and 3 as cut away to show the two sides of the relay.

The mounting plate 14 is preferably made of brass and is secured to the Bakelite base plate 10

55

by means of the screws 11 and 12. The inductors 15, 16 suitably wound for any desired frequency are mounted on the laminated iron core 17 which is tightly clamped between brass plates 18, 19 by means of the screws 20, 21 which also assemble the magnetic circuit parts to the mounting plate 14.

Two inductors 15, 16 are employed to obtain the total required inductance, the value of which may be varied over a narrow band of frequencies 10 by connecting the coils-series-aiding or series-bucking and also by varying the spacing 43 between the coils to change their mutual inductance.

The space 43 can be varied by having the coils 15 a pressed fit on their iron core and by moving one relative to the other, or the coils can be a sliding fit and can be relatively moved until the proper adjustment is obtained, whereupon some quick-drying cement is placed in the space 43 between 20 the coils and the core to hold the coils fixed in the desired position, or they can be fixed to the core in any other manner.

The brass plates 18, 19 have extensions 22, 22a at one end as shown to provide space for tapped holes to accommodate case hardened pivot screws 23.

A slot 25 is cut in from one edge of the plates to the tapped holes to provide means for applying tension to the threads of the pivot screws to hold them securely without the aid of jam nuts.

The soft iron armature 26 is assembled by holding the vertical portion tightly against the poles of the iron core and adjusting the pivot screws to firmly engage the edges of the armature, and this manner of assembly eliminates the possibility of a reluctance gap at the pivoting point thereby minimizing magnetic leakage and concentrating the greatest magnetic flux at the opposite pole.

As the pivot screws are sharply pointed, the armature is delicately poised to move freely, and yet is securely held in operating position at all times.

An insulating plate 24 is assembled to the mounting plate 14 by means of screws 14a and 14b and carries the contact spring 27, spring tensioning screw 28 and adjustable contact screw 29.

Movement of the armature 26 is conveyed to the contact spring 27 by means of an insulating pin 30. The adjustment of the armature and the switch just described is accomplished by setting the air gap between the long leg 26a of armature 26 and the pole face 31 of the iron core by means of adjusting screw 32 and spring tensioning screw 28 to hold the armature lightly against screw 32, and then adjusting the screw 29 to allow the switch contact to close as the armature is attracted to the pole face 31.

The form of switch above described affords greater accuracy of adjustment with a resultant increase in relay sensitivity as compared with ordinary types of commercial switches used on previous devices, as it has been found that ordinary types of switches such as that shown in the co-pending application before mentioned cannot be obtained in quantities to meet the uniform pressure and over-travel specifications necessary in a device of this character.

The switch herein described is merely illustrative of any spring-biased device operable to open or close contacts or to switch electrical circuits in any manner; or this device may be Sylphon bellows or other pressure varying or responsive device adapted to control a valve or the like.

As such devices are of numerous types and are all well known, same are not described in detail as obviously any biased device can be used, depending on the function desired.

It will also be obvious that the pressure of the contact spring 27 or other equivalent member is communicated to the armature 26 and aids in the tuning of the relay.

In Fig. 3, the dust cover 13 is cut away to show the reverse side of the relay. The capacitor 33 is secured to the mounting plate 14 in any suitable manner and may be held thereto by means of the insulated lead wires 34, 35 which pass through holes in the mounting to the opposite side of the assembly.

In Fig. 4 the dust cover 13 is removed and the switch and condenser assemblies omitted to clearly show the assembly of the magnetic circuit to the mounting plate 14. The excess space shown 20 has been provided to allow assembly of a vertical bracket to the base plate 10 upon which the condensers may be mounted when two or more parallel connected capacitors or condensers are required to tune to low frequency.

Figure 5 is an enlarged view showing the details of the armature suspension and adjustment previously described and is self-explanatory.

The electrical circuits not shown are very simple in that the inductors and condensers are merely connected in series. This may be accomplished by connecting the condenser lead 34 to a small pin 44 on plug 36. The latter would connect to the line or circuit in which the relay is used, the other side of said circuit would connect to the small pin 45 which connects to terminal 37 on one of the inductors 15.

The other terminal 38 on this inductor is connected to a terminal 39 on the second inductor 16 (the inductors being connected series-aiding or bucking as required). The other terminal 40 on the second inductor 16 is connected to the second condenser lead 35, thus completing the internal circuit of the relay.

The internal circuit to the switch or other spring biased device is made from the large pins 46, 47 which connect to the terminals 41, 42 on contacts 27 and screw 29.

What is claimed is:

1. In a tuned relay responsive to a predetermined frequency, a pair of windings; a U-shaped core comprising a plurality of laminations, said windings being mounted on one leg of said core and being relatively movable therealong to vary the predetermined frequency, the free ends of said core extending outwardly beyond the end of the outermost winding thereon, means extending transversely of the exposed leg of said core for securing said laminations together, an L-shaped armature one leg of which extends across the free ends of said core, the other leg of same extending along the exposed side of said core toward the closed end thereof, a support for said core, means carried by said support for movably securing said armature in rockable relation to said core, a contact spring overlying a portion of said armature to be actuated thereby, a contact member mounted on said support and adapted to cooperate with said contact spring, and means mounted on said support for adjusting said armature relative to said core.

2. The relay as claimed in claim 1 wherein said means for movably securing said armature to said core comprises pins extending through apertures 78 in said armature and into said core whereby same

is rockably supported thereon and in direct metallic contact therewith.

3. In a tuned audio relay responsive to a predetermined frequency, a base plate; a plate-like support mounted on said plate and extending in a plane perpendicular thereto; an alternating current electromagnet secured to the flat side of said support and comprising a U-shaped core of a plurality of laminations; a pair of windings mounted on one leg of said core and being relatively movable therealong to vary the predetermined frequency; the free ends of said core extending outwardly beyond the outermost winding thereon; an L-shaped armature one leg of which extends across the free ends of said core, the other leg of said armature extending along the exposed end of said core toward said base plate; means carried on said plate-like support for movably securing said armature in rockable relation to said core; adjusting means mounted on said plate-like support adapted to contact said armature to adjust the same where it overlies the free ends of said core; and a control device mounted on said plate-like support engaged by said armature for operation thereby.
